[57] CLAIM

The ornamental design for a shielded reset lever for a firewall-mount high amp circuit breaker, as shown and described.

DESCRIPTION

FIG. 1 is a top, front and right side perspective view of a shielded reset lever for a firewall-mount high amp circuit breaker showing our new design with the lever in the tripped position;

FIG. 2 is a top plan view thereof;

FIG. 3 is a right side elevational view thereof;

FIG. 4 is a left side elevational view thereof;

FIG. 5 is a front elevational view thereof; and,

FIG. 6 is a rear elevational view thereof.

The broken line showing of the circuit breaker is included for the purpose of illustrating environmental structure only and forms no part of the claimed design.
